UNITED STATES PATENT OFFICE.

WALTER S. SIMPSON, OF CANTON, OHIO, ASSIGNOR TO THE UNITED ELECTRIC COMPANY, OF CANTON, OHIO, A CORPORATION OF OHIO.

VACUUM-CLEANER ATTACHMENT.

Application filed August 20, 1926. Serial No. 130,534.

The invention relates to nozzle attachments for vacuum cleaners, wherein it is desired to cover the rim of the mouth of the nozzle with felt; and the object of the improvement is to 5 provide means for easily and readily securing such an attachment to the nozzle and removing the same therefrom when it is desired to use the nozzle without the felt or brush attachment.

10 The object of the improvement is to provide an attachment for a suction cleaner nozzle which may be provided with floor engaging means, such as felt strips or pads, or the like, for covering the rim of the nozzle mouth, 15 and provided with pivoted bails for engagement over the ends of the nozzle, clamping screws being carried by said bails for clamping the attachment rigidly in position upon the nozzle.

20 An embodiment of the invention is illustrated in the accompanying drawing, in which

25 Figure 1 is a side elevation of a suction cleaner nozzle showing the improved attachment connected thereto;

Fig. 2, a top plan view of the attachment;

Fig. 3, a section taken substantially on the line 3—3, Fig. 1, and

Fig. 4, a section on the line 4—4, Fig. 1.

30 Similar numerals refer to similar parts throughout the drawing.

The nozzle may comprise the tubular shank 1 and the lateral elongated, flattened mouth portion 2 terminating in the straight parallel 35 rims 3. The tubular shank 1 is arranged to be connected as by a hose or the like, to the vacuum cleaning machine in the usual manner.

For the purpose of preventing the nozzle from marring furniture with which it may 40 come in contact during the cleaning operation, a heavy cord or rope 4 may be located in a groove 5 formed around the nozzle near the lips of the mouth.

The nozzle may be used in this form for the 45 cleaning of carpets and the like, and the felt attachment may be connected thereto for cleaning hardwood floors, upholstering, and the like.

The attachment illustrated in the drawing 50 is provided with felt strips or pads adapted for engaging and cleaning hardwood floors and similar surfaces, but it should be understood that other attachments may be connected to the nozzle in the same manner.

The attachment comprises a frame, preferably formed of aluminum and comprising the parallel side bars 6, to each of which is connected a strip or pad 7 of felt, as by the screws 8.

Blocks 9 are located at the ends of the attachment, between the felt pads, for separating the same, screws 10 being passed through the side bars 6 and felt pads 7 into said blocks.

The side bars 7 are provided at their ends with the upright ears 11 to each pair of which is pivoted, as at 12, a clamping bail 13, provided at its center with a clamping screw 14 having a suitable knurled head to permit easy operation of the same.

When it is desired to connect this attachment the rim of the nozzle is placed upon the top of the attachment and the bails 13 are swung into substantially upright position as best shown in Figs. 1 and 4, the clamping screws 14 then being tightened, the ends thereof engaging the sockets 15 in the upper side of the nozzle pressing and engaging the rim of the nozzle tightly upon the felt pads 7 and clamping the attachment firmly upon the nozzle.

80 The nozzle with this attachment fixed thereon may then be used for cleaning hardwood floors and the like, the felt pads contacting with the surface of the floor as the tool is moved over the same and assisting in polishing the floor as it is cleaned.

85 When it is desired to again use the nozzle without the attachment it is only necessary to loosen the clamping screws and swing the bails outward into substantially the position 90 shown at the left side of Fig. 2, permitting the nozzle to be quickly disengaged from the attachment.

I claim:

95 In combination with a nozzle provided with ends and having a mouth rim, an attachment for engagement with said rim and having floor engaging means, bails pivoted upon the attachment for engagement over the ends of the nozzle and means upon the 100 bails for clamping engagement with the nozzle.

In testimony that I claim the above, I have hereunto subscribed my name.

WALTER S. SIMPSON.
